UNITED STATES PATENT OFFICE.

RICHARD E. SAGE, OF PAW PAW, MICHIGAN.

SIGN-BOARD.

No. 829,090.

Specification of Letters Patent.

Patented Aug. 21, 1906.

Application filed March 1, 1906. Serial No. 303,691.

To all whom it may concern:

Be it known that I, RICHARD E. SAGE, a citizen of the United States, residing at Paw Paw, in the county of Van Buren and State of Michigan, have invented certain new and useful Improvements in Sign-Boards, of which the following is a specification.

This invention relates to improvements in sign-boards.

10 The main object of this invention is to provide an improved sign-board on which the signs are quickly and easily changed as desired and one which is very economical to produce and very durable in use.

15 Further objects and objects relating to structural details will definitely appear from the detailed description to follow.

I accomplish the objects of my invention by the devices and means described in the 20 following specification.

The invention is clearly defined and pointed out in the claims.

A structure embodying the features of my invention is clearly illustrated in the accompanying drawings, forming a part of this 25 specification, in which—

Figure 1 is a front view of my improved sign-board. The sign-cards are shown in blank, the sign-board illustrated being divided 30 into "For sale" and "Wanted" columns, with sign-cards in position having those words thereon. Fig. 2 is a detail section on line 2 2 of Fig. 1, showing the form of the card-holding tongues *a*. Fig. 3 is a detail section on a 35 line corresponding to line 3 3 of Fig. 1, showing the form of card-stops *a*.

In the drawings the sectional views are taken looking in the direction of the little arrows at the ends of the section-lines, and 40 similar letters of reference refer to similar parts throughout the several views.

Referring to the drawings, the body of my improved sign-board is formed of a piece of sheet metal. The sides are turned outwardly 45 into flanges *A'* for holding the cards in place and also to add to the rigidity of the board. The top and bottom edges are turned into in-turned flanges *A''*, which add to the strength of the board and also coact in holding the top 50 and bottom cards, as will be pointed out. A plurality of hook-like card-holding tongues *a* are punched up from the body of the board. These are arranged oppositely, the tongues for engaging adjacent edges of the sign-cards 55 being preferably in alinement, thereby utilizing

practically all of the surface of the board for display-cards. In the structure illustrated I provide a double series of card-holding tongues, so that two columns of matter may be displayed. End stops, as *a'*, are provided for the cards, and these stops in the double-column structure illustrated are located between the columns, so that they serve for both, the cards being introduced or inserted in the holders from the outside. In 60 the structure illustrated I have inserted a card designating articles for sale in one column and in the other a card for articles wanted. The top and bottom flanges *A''* are arranged to coact with the top and bottom series of card-holding tongues for holding display-cards, preferably arranging in the top holder a card *B*, giving the name of the proprietor. This bill-board is especially designed for the use of farmers, where the frequent changing of the articles advertised is required. The cards *B'* shown are intended for item-cards. By this means the announcement of any article for sale or wanted can be displayed and changed as conditions 75 require. The card *B''* is intended by me to receive some general advertisement, although, of course, it may be utilized as desired.

It is evident from the foregoing that my 80 improved sign-board is very economical to produce and that it is very durable. If desired, the announcement or sign cards may be printed on tin or similar material. It is evident that by the arrangement described I 85 utilize practically all of the face of the bill-board, and at the same time the announcement-cards are held so that they may be readily changed and not in any way damaged by inserting or removing.

Having thus described my invention, what I claim as new, and desire to secure by Letters Patent, is—

1. In a sign-board, the combination of a body portion formed of sheet metal, having 90 inturned flanges at its top and bottom and outturned flanges at its sides; oppositely-arranged hook-like card-holding tongues formed by punching up portions of said body, the tongues for engaging the adjacent edges 95 of the cards being arranged in alinement, said top and bottom flanges of said body being arranged to coact with the top and bottom card-holding tongues to form card-holders; cards adapted to be slipped under said 100

95

110

tongues; and end stops for said cards formed by punching up lugs from said body, for the purpose specified.

2. In a sign-board, the combination of a body portion formed of sheet metal, having inturned flanges at its top and bottom and outturned flanges at its sides; oppositely-arranged hook-like card-holding tongues formed by punching up portions of said body, 10 the tongues for engaging the adjacent edges of the cards being arranged in alinement, said top and bottom flanges of said body being arranged to coact with the top and bottom card-holding tongues to form card-holders; 15 and cards adapted to be slipped under said tongues, for the purpose specified.

3. In a sign-board, the combination of a body portion formed of sheet metal having outturned flanges at its sides; oppositely-arranged hook-like card-holding tongues formed by punching up portions of said body; cards adapted to be slipped under said tongues; and end stops for said cards formed by punching up lugs from said body, for the purpose specified. 20

In witness whereof I have hereunto set my hand and seal in the presence of two witnesses. 25

RICHARD E. SAGE. [L. S.]
